UNITED STATES PATENT OFFICE.

LAWRENCE J. ZAHN, OF LONG ISLAND CITY, NEW YORK, ASSIGNOR TO INTERNATIONAL POSTAL SUPPLY COMPANY, OF BROOKLYN, NEW YORK.

MAIL-MARKING MACHINE.

Application filed August 1, 1925. Serial No. 47,496.

This invention relates to a mail marking machine which separates the mail matter and then cancels the stamp, or post-marks the piece of mail.

5 It is the principal object of my present invention to provide a machine for this purpose which is especially adapted to be operated by hand, there being a certain demand for canceling or post marking machines of 10 this kind.

Another object of my invention is to provide a hand operated mail marking machine which includes many of the features of the more expensive power actuated machines, 15 yet, eliminating many of the parts used in such power operated machines and simplifying the full combination.

Another object of my invention is to provide a machine which is readily portable 20 and one in which the operating parts may be readily reached for the purpose of inspection and adjustment.

These and other objects will be apparent to one skilled in this art after a consideration 25 of the specification taken in connection with the annexed drawings, wherein

Figure 1 is a side view of the machine, a part of the hand operating wheel being broken away to show the parts behind it.

30 Figure 2 is a plan view of the machine.

Figure 3 is a view of the back of the machine with the side of the gear housing removed to show the interior parts.

Figure 4 is an end view of the machine 35 looking at the right of Fig. 1.

Figure 5 is a detailed view of some of the operating parts.

Figure 6 is a perspective view of the separator roller and its operating wheel.

40 Figure 7 is a view of the die structure and its support.

Figure 8 is a partial side view of the trip mechanism shown in Fig. 7.

Figure 9 is a view of the left hand end of 45 Fig. 7.

Figure 10 is a part sectional view of the combination printing and trip pressure and stacker feed roller.

Figure 11 is an end view of one part of 50 the roller looking to the left on the line 11-11.

Figure 12 is a view of the other part of the roller looking to the right of the line 11-11 of Fig. 10.

55 Figure 13 is a part sectional view of the

trip pressure part of the combination roller shown in Fig. 10.

Figure 14 is a detail of a part of the stacker mechanism.

Figure 15 is a fragmentary detail showing 60 the connection between the main drive wheel and the drive shaft.

Referring now to the details wherein like numbers refer to corresponding parts in the various views, 1 is a base having a gear 65 housing 2 extending therefrom. The base 1 also carries a bracket or support member 3 which assists in carrying a feed table 4 on which the mail to be marked is placed for feeding to machine. A main operating 70 shaft 5 is supported by a part of the housing 2 and the support 3. On the outer end of the shaft 5 is operatively connected a hand wheel 6 having a handle 7 for turning the shaft. Either the hub of the wheel 6 75 or a shaft 5 has fastened thereto a ratchet wheel 8 to cooperate with a pawl 9 carried on the support 3, the object of which is to provide means whereby the shaft can be turned only in one direction and that, the 80 proper one. Within the housing 2 and on the end of the shaft 5 is carried a large gear wheel 10. In mesh with the gear wheel 10 is a pinion 11 which is fastened to a shaft 12 that operates the die structure 13. The 85 die structure is composed of a die similar to that shown in Jahn Patent 856,345 issued June 11, 1907, while the clutch arrangement for controlling the die is the same as described in my joint application with John 90 A. Mitchell Serial No. 749,961 filed November 14, 1924, and, therefore, these parts will not be described in detail. Likewise, the trip mechanism illustrated generally by the 95 numeral 14 in Figures 7 and 8, is the same as that shown in said Jahn patent and will not be described in detail herein.

As will be seen in the drawings, the die structure and trip mechanism is carried on a bracket 15 attached to the housing 2. It 100 will, however, be understood that the part 16 of the die structure is attached to the shaft 12 and is continuously turning with the shaft 12 while the die 13 is held from turning by the stop 17 against the pin 18 105 in the end of the die until such time as the stop 17 is removed from the path of the pin 18 by the trip mechanism 14 which is actuated by the mail matter hitting the end 19 of the trip lever. The pinion 11 carries pins 110

20 which engage the star wheel 21 fastened to a shaft 22 which in turn is carried on a lever 23 pivoted to the housing at 24. The opposite end of the shaft 22 carries a separator roller 25 which acts to separate the pieces of mail matter as they are brought forward by the large feed roll 26 that is mounted directly on the shaft 5 intermediate its bearings. The position of the shaft 22 10 and the separator roller 25 is adjusted by means of the rod 27 and the thumb nut 28. The housing 2 also carries an inker 29 that is mounted on an adjustable arm 30.

Associated with the die structure 13 and 15 the continuously rotating part thereof 16, is a combination roller consisting of two parts 31 and 32. The part 31 is mounted to rotate on a shaft 33 carried on an arm 34 which in turn is pivotally mounted on the pivot pin 20 35, the arm 34 being extended and jointed at 36 to an adjusting stud 37 which, through the action of the spring 38 and thumb nut 39, can be raised and lowered thereby varying the position of the roller 31, known as 25 the printing pressure roller that engages the surface of the die per se as the same is turned after it has been released as previously referred to. It is to be understood that when 30 the die 13 is not turning, the printing pressure roller 31 is opposite a cut-away or depressed portion of the surface of the die and is therefore not in contact with it. The end 35 of the printing pressure roller 31 has a projecting part or tongue 40 which is adapted to be positioned in a groove 41 in the trip pressure roller 32. There is sufficient clearance between the groove 41 and the tongue 40 to provide for the adjustment of the part 31 by means of the thumb nut 39 as has been 40 described. The part 32 constituting the trip pressure part of the combination roller is pivoted on an arm 42 to the end of which a spring 43 is attached to continuously hold the part 32 against the member 16 as shown 45 in the dotted line in Fig. 7. The two parts 31 and 32 as above described together constitutes a stacker feed roller, that is to say, they act to carry the mail past the die and into the stacker which will now be described.

50 Carried by the base is a plate 44 which is preferably slidable in grooves in the base and adapted to be held in any adjustable position as shown in the dotted lines of Figs. 1 and 2 by means of a set screw 45. The plate carries guide members 46. Similar guide members are also attached to the stationary part of the base thereby constituting the back of the stacker pocket, the front of 55 which pocket is closed by a pair of similar guide members which are attached to a rotatable member 47. One side of the member 47 has a flat portion against which a plunger 48 is positioned. A spring 49 serves to push the plunger 48 continuously against the member 47 thereby tending always to hold it

in a position such that the guide members 46 are in an upright position, but, when it is desired to take the mail from the stacker pocket, a slight pressure on the upper ends of one of the members 46 carried by the rotatable member 47, is sufficient to turn these particular members to a horizontal position as indicated by the dotted lines in Fig. 2 thereby allowing the stacker pocket to be opened in order to easily get at the mail 75 matter. The back of the stacker pocket is closed by a pair of members 50 which have their upper ends curved inwardly toward the separator roller and on an arc approximating that of the circumference of the large 80 feed roller 26. These curved ends serve to guide the mail matter into the stacker pocket. In order to insure that the mail matter lands in the pocket after coming through the machine, a flexible member 51 85 preferably in the form of a flat spring is positioned over the pocket so that, as the mail hits it, the flapper spring 51 throws or guides the mail matter into the pocket. The spring 51 serves an additional function in 90 that its inner end 52 extends at a point so as to act as a tension spring on a part of the trip mechanism as more clearly shown in Fig. 8.

It may also be mentioned that the machine 95 carries a magazine 53 in which is carried the type for resetting the die from day to day.

From the preceding it is believed that the operation of the machine will be clearly understood, but, it should be observed that 100 the various details herein described may be varied without departing from the new features of my invention which are specifically claimed herein.

Having thus described my invention what 105 I claim is:

1. In a mail marking machine, a base, a housing extending from the base, a main operating shaft having a support in said housing, an inker and a separator roller both 110 adjustably carried on the housing, a printing die and trip mechanism therefor and a printing pressure roller also carried on the housing and a single feed roll carried directly on said shaft in cooperation with the 115 separator roller.

2. In a mail marking machine, a base, a housing extending from the base, a main operating shaft having a support in said housing, an inker and a separator roller both 120 adjustably carried on the housing, a printing die and trip mechanism therefor and a printing pressure roller also carried on the housing, a single feed roll carried directly on said shaft in cooperation with the separator roller, a stacker plate adjustable on the base, guide members on the base and plate forming a stacker pocket; one pair of guide members on the base being arranged, one 125 on either side of said feed roll, and having 130

their free ends curved toward the separator roller.

3. In a mail marking machine, a base, a housing extending from the base, a main operating shaft having a support in said housing, an inker and a separator roller both adjustably carried on the housing, a printing die and trip mechanism therefor and a printing pressure roller also carried on the housing, a single feed roll carried directly on said shaft in cooperation with the separator roller, a stacker plate adjustable on the base, guide members on the base and plate forming a stacker pocket; one pair of guide members on the base being arranged, one on either side of said feed roll, and having their free ends curved toward the separator roller, and a flexible member carried adjacent the housing so one end extends over the top of the pocket for the purpose described and the other end acting as a tension spring on a part of the trip mechanism.

4. In a mail marking machine including a main drive shaft, a printing die operated from said shaft, a trip mechanism for the die, a single feed roll carried on the shaft, a separator roller, a printing pressure roller, a stacker pocket adjacent said feed roller and a flexible member mounted so one end extends over the top of the pocket for the purpose described and the other end acting as a tension spring on a part of the trip mechanism.

5. In a mail marking machine including a main drive shaft, a printing die operated from said shaft, a trip mechanism for the die, a single feed roll carried on the shaft, a separator roller, a combined printing and trip pressure roller and an adjustable stacker pocket adjacent said feed roller.

6. In a mail marking machine including a main drive shaft, a printing die operated from said shaft, a trip mechanism for the die, a single feed roll carried on the shaft, a separator roller, and a combination roller cooperating with the die structure acting as a printing and trip pressure roller as well as a stacker feed roller.

7. In a mail marking machine including a die structure and a trip mechanism for controlling the operation of the die, means for feeding mail matter past the die, means for operating the die and a combination roller cooperating with the die structure acting as a printing and trip pressure roller as well as a stacker feed roller.

8. In a mail marking machine including a die structure and a trip mechanism for controlling the operation of the die, means for feeding mail matter past the die, means for operating the die and a roller comprising two parts having relative movement therebetween, one part engaging the die when it turns and the other normally engaging a

part of the die structure in continuous motion while the machine is being operated.

9. In a mail marking machine including a die structure and a trip mechanism for controlling the operation of the die, means for feeding mail matter past the die, means for operating the die, a roller comprising two parts having separate bearings but one part being driven by the other, one of said parts acting as a printing pressure roller and the other part as a trip pressure roller.

10. In a mail marking machine including a die structure and a trip mechanism for controlling the operation of the die, means for feeding mail matter past the die, means for operating the die and a combination roller comprising; a part normally held under spring tension against a continuous moving part of the die structure, and another part adapted to engage the die when it turns and means for adjusting the relative position of said two parts.

11. In a mail marking machine including a die structure and a trip mechanism for controlling the operation of the die, means for feeding mail matter past the die, means for operating the die and a combination roller comprising; a part normally held under spring tension against a continuous moving part of the die structure, and another part adapted to engage the die when it turns, a tongue in one part of the combination roller and a groove in the other part for completing a driving connection between the two and means for adjusting one part with respect to the other.

12. In a mail marking machine including a die structure and a trip mechanism for controlling the operation of the die, means for feeding mail matter past the die, means for operating the die and a combination roller comprising; a part normally held under spring tension against a continuous moving part of the die structure, and another part adapted to engage the die when it turns, said parts being axially spaced and having an adjustable driving connection therebetween.

13. In a hand operated mail marking machine, a base, a gear housing extending upward from said base, a main drive shaft having a bearing in said housing and an outboard bearing supported on said base, an operating handle on the outer end of said shaft, a main driving gear on the shaft within the housing, a die structure supported by the housing and having a gear in mesh with said main gear, a trip mechanism for the die carried by the housing, a single feed roll carried on the shaft intermediate its bearing, a separator roller adjustably carried by the housing and a combined printing and trip pressure and stacker feed roller adjacent the die structure.

14. In a hand operated mail marking ma-

chine, a base, a gear housing extending upward from said base, a main drive shaft having a bearing in said housing and an out-board bearing supported on said base, an operating handle on the outer end of said shaft, a main driving gear on the shaft within the housing, a die structure supported by the housing and having a gear in mesh with said main gear, a trip mechanism for the die carried by the housing. A single feed roll carried on the shaft intermediate

its bearing, a separator roller carried by a stub shaft operated from said die gear, an adjustable lever pivoted on said housing for supporting said stub shaft, a combined printing and trip pressure and stacker feed roller adjacent the die structure and operated therefrom and a stacker comprising a plate adjustable on said base and guide members on both the base and plate. 15

In testimony whereof, I affix my signature.

LAWRENCE J. ZAHN. 20
